UNITED STATES PATENT OFFICE.

HENRY GATES, OF BROOKLYN, NEW YORK, ASSIGNOR OF ONE-HALF TO
JAMES J. MATCHETT, OF SAME PLACE.

VENDING APPARATUS.

SPECIFICATION forming part of Letters Patent No. 393,149, dated November 20, 1888.

Application filed February 10, 1888. Serial No. 203,567. (No model.)

To all whom it may concern:

Be it known that I, HENRY GATES, of Brooklyn, in the county of Kings and State of New York, have invented a new and Improved 5 Vending Apparatus, of which the following is a full, clear, and exact description.

My invention relates to apparatus for retailing or delivering articles or goods in exchange for coin, and has for its object to provide a 10 machine of this character which will be simple of construction and easy and accurate of operation, it being rendered impossible to work the same by means of a coin of a denomination other than that arranged for.

15 My invention is embodied in the construction and combination of parts hereinafter described and claimed.

Reference is to be had to the accompanying drawings, forming a part of this specification, 20 in which similar letters of reference indicate corresponding parts in all the figures.

Figure 1 is a perspective view of my apparatus complete. Fig. 2 is a central vertical section of the same. Fig. 3 is a horizontal section on the line $x-x$ of Fig. 2, part of the lower easing of cabinet being broken away, showing the interior. Fig. 4 is a disassembled view of the parts through which the coin passes. Fig. 25 5 is a view in detail, showing the lower end of one of the magazine-tubes. Fig. 6 is a detailed view of the slide or drawer. Fig. 7 is a view in perspective of a weight-block working within the magazine-tubes.

In the drawings, A represents a cabinet composed of the base or lower part, a , and the upper portion, a' . Journaled in the top and bottom of this cabinet and passing centrally through the same is a shaft, B, which carries the rotating magazine C, containing the supply 40 of goods to be delivered to the drawer.

The magazine is made up of a number of vertical tubes, D, into which the goods made up in packages are placed, and from which they are delivered to the sliding drawer. Each 45 and every tube has across its outer face a label, d , designating the article contained in the respective tube, so that the purchaser may bring the tube containing the desired class of goods in position directly above the sliding drawer, the label showing through the aper-

ture a^2 for that purpose. For working the magazine in this manner, I have provided on the front of cabinet A, a dial, E, having labels or inscriptions to correspond with those on the tubes D. By turning the hand e to the 55 desired class of goods indicated on dial E, the tube containing the class of goods corresponding is brought to position over the drawer. The hand e is mounted on the spindle F and on the other end of said spindle bevel-gear f 60 is mounted, which meshes with bevel-gear b on shaft B, thus giving the necessary rotary motion to the magazine C. After filling the tubes D with packages, the bottom one of which rests on inwardly-projecting ears d' , I place on 65 top of the column a weight-block, G, having a T-shaped projection, g , on which is inscribed the word "Empty." This projection g works on the outside of the tubes D, so that when the supply of packages in the tubes D becomes 70 low the weight-block G will descend to a position in alignment with the aperture a^2 of the cabinet, and the word "Empty" on the projection g thereof will show through, so that the magazine may be replenished through the 75 hinged panel in the cabinet. (Shown in Fig. 1.)

H is the delivery drawer or slide, provided with projecting blocks or lugs h . Interposed between this drawer H and a central slat in the cabinet is a spiral spring, I, for forcing the 80 drawer out when the same has been released. When the drawer H is in a closed position, one end of a bent lever, J, will set in between the lugs h . This bent lever is secured by staples a^3 to the base of cabinet A, and has a dip or 85 half-round bend, j , so that it will come below the plane of rotation of the magazine C. On one end of the lever J there is a small depending lug, j' .

Working in the base of cabinet and to one 90 side of the drawer H is a slide, K, having a slot, k , and forced out by a spiral spring, k' , seated between the said slide K and a central slat in base of cabinet. The slide K works on and over a short bar, L, secured to the cabinet 95 A, and said bar L has a slot, l , of a size to correspond with the slot k in the slide K. When the slide K is in its normal position out from the front wall of the cabinet A, the slot l in the bar L is in the rear of it; but when the slide 100

K is pushed in against the spring k' the slots k and l register, and both being of a size to admit a coin of the proper denomination the coin passes fully through the same.

5 M is a lever having a fulcrum in a bracket, N, and having an L-shaped arm, m, which carries a balance-weight, O, and a pawl, P. On the other end of the lever M there is a head, m', having a concave depression therein, into 10 which the coin fits after passing through the slots k and l. The coin being of a weight sufficient to overcome the balance-weight O on the other end of the lever M, the said lever is tilted and descends to an inclination which dislodges 15 the coin from the depression in the head m', and it is thrown on the floor of the cabinet. The lever M being free of the coin, the weight O carries the said lever back to its normal position, and in so doing the pawl P engages a 20 toothed wheel, Q, secured to the end of a roller, R, journaled in brackets in the rear of the cabinet A.

In the upper part, a', of the cabinet A there is hung in suitable brackets a roller, S, over 25 which and the roller Q an endless ribbon, T, passes. On the ribbon T is printed advertisements, choice extracts from well-known authors, or other reading-matter that may be found to be of interest to the general public. 30 This reading-matter on the ribbon will show through an open panel, U, in the cabinet A.

The operation is as follows: The purchaser turns the hand e on the dial E to the desired class of goods, this bringing the corresponding tube, D, of the magazine in position directly above the drawer H, which is in the cabinet A, while the slide K is out from the cabinet. The proper coin is now dropped into the slot marked "Coin." It passes through 35 slot k in the slide K, and rests on the bar L, immediately in advance of the slot l. The coin having a diameter greater than the thickness of the slide K, it projects from the upper face of slide just in front of the lug j' of the bent 40 lever J. The slide K is now pushed in toward the cabinet, which movement causes the coin to first strike the lug j' of the lever K, giving the same a rotation sufficient to throw the other end up from its seat between the lugs h 45 and h' of the drawer H, releasing the drawer and allowing the spring k' to move the drawer H outward, the lug h carrying the bottom package off the ears d' and through the open front 50

of the tube D, and as the delivery-drawer projects its full length the package can be removed. 55

The slide K being released by the purchaser, the spring k' throws it out to the initial position. The drawer at the same time must be pushed in, when the end of lever J will ride up the beveled face of lug h to its seat between 60 the lugs h and h', thus locking the drawer again. After the coin has passed through slots k and l, it lodges in the depression in the head m' of the lever M, tilting the same to an inclination sufficient to throw the coin to the floor 65 below. The lever M being relieved of the coin, the weight O returns said lever to its horizontal position, which movement causes the pawl P to engage the toothed wheel or the roller R and turns the same, thus giving the ribbon T 70 a movement and displaying a new reading.

Having thus described my invention, what I claim as new, and desire to secure by Letters Patent, is—

1. In a vending apparatus, the combination, 75 with tube D, having at the bottom inwardly-projecting ears d', and notched, as shown, of the drawer H, having lugs h and h', the spring I, tending to push the drawer out, the slotted slide K and its spring k', and the bent lever 80 J, having its ends bent, as shown, to enable it to come into contact with the lug h' and to be relieved therefrom by the slide when a coin is inserted in the slot in said slide, all as herein-before described. 85

2. In a vending apparatus, the combination, 90 with the revolving magazine carrying the goods to be delivered, consisting of vertical tubes mounted on a vertical shaft, of the spring-actuated drawer H, provided with the lugs h 90 h', the bent lever J, having lug j', and of the coin-carrying slide K, substantially as herein shown and described.

3. In a vending apparatus, the combination, 95 with the coin-carrying slide K, slotted to receive the coin and working on a correspondingly-slotted bar L, of the lever M, having a head, m', balance-weight O, and pawl P, the roller R, having a toothed wheel, the roller S, and ribbon T, substantially as shown and described. 100

HENRY GATES.
